Specification for Design.

Patented Mar. 31, 1914.

Application filed November 28, 1913. Serial No. 803,427. Term of patent 7 years.

To all whom it may concern:

Be it known that I, CARL W. TILLMANNS, a citizen of the United States, residing at Utica, in the county of Oneida and State of New York, have invented a new, original, and ornamental Design for the Handle of a Knife, of which the following is a specification, reference being had therein to the accompanying drawing.

My invention relates to a new, original, improved and ornamental design for the handle of a knife, of which the following is a specification, reference being had therein to the drawings.

In the drawing the figure is a plan view

of the design with the ornamentation or stripes which may run in given direction and may be of a different variety of colors, as is indicated by the lines on the design as shown.

I claim:

The ornamental design for the handle of a pocket knife, as shown.

In testimony whereof I hereunto affix my signature in the presence of two witnesses.

CARL W. TILLMANNS.

Witnesses:

HENRY M. LOVE,
ELEANOR T. DE GIORGI.
